UNITED STATES PATENT OFFICE.

CHARLES F. SMITH, OF WATERTOWN, NEW YORK, ASSIGNOR TO HOWLAND BAG AND PAPER COMPANY, OF DEXTER, NEW YORK, A CORPORATION OF NEW YORK.

PAPER-BAG MACHINE.

1,333,285.

Specification of Letters Patent. Patented Mar. 9, 1920.

Application filed August 14, 1918. Serial No. 249,854.

To all whom it may concern:

Be it known that I, CHARLES F. SMITH, a citizen of the United States, and a resident of Watertown, in the county of Jefferson and State of New York, have invented 5 certain new and useful Improvements in Paper-Bag Machines, of which the following is a specification.

This invention relates to paper bag machines of that class which is provided for forming from tubular blanks, having opposite inwardly folded tucks, paper bags commonly known as self-opening square paper bags.

15 My improvements pertain directly to those parts of such a paper bag machine as are provided for forming the well known diamond fold on the leading end of the bag blank.

20 The object of my improvements is to provide means of simple construction which are reliable and accurate in their operation, for coaction with known means, for improving, both in quality and quantity, the product 25 of paper bag machines of the class specified.

To these ends my improvements comprise features which are illustrated in their preferred embodiment in the drawings accompanying this specification, wherein:

30 Figure 1 is a fragmentary side elevation, partly in section on line 1, 1 of Fig. 2, of so much of a paper bag machine as will suffice to illustrate those parts thereof which 35 perform the earlier steps in the operation of my improvements. Fig. 2 is an elevation looking in the direction of arrow 2^a of Fig. 1, with some of the parts of said Fig. 1 omitted. Figs. 3, 4, 5 and 6 are side elevations, respectively, similar to a portion of 40 what is shown in Fig. 1 and illustrating successive steps in the operation of the mechanism. Fig. 7 is a side elevation, similar to the side elevation of Fig. 1, showing a 45 part of what is shown in said Fig. 1 and illustrating an early step in the operation of opening out the leading end of the bag-blank preparatory to forming the diamond fold. Figs. 8, 9, 10, 11, 12, 13 and 14 are 50 side elevations respectively similar to a portion of what is shown in Fig. 7 and illustrating successive steps in the operation of the mechanism in forming the diamond fold. Fig. 15 is a plan view looking in the 55 direction of arrow 15^a of Fig. 7, with some

of the parts of said Fig. 7 omitted, so as to show more clearly the operation of the mechanism. Fig. 16 is a plan view looking in the direction of arrow 16^a of Fig. 9. Fig. 17 is a plan view looking in the direction of arrow 17^a of Fig. 14. The vertical dot and dash lines 2, 2 in Figs. 1, and 3 to 14 inclusive are in the same position relatively to the fixed parts of the machine. All the figures of the drawings are to the same 65 scale.

The improvements illustrated and described herein while applicable to a variety of types of paper bag machines are particularly applicable to a paper bag machine 70 of the general character of that shown in Letters Patent No. 1,074,330, granted on my application, dated September 30, 1913, and to which reference may be had.

The general plan of paper bag machine 75 to which I have chosen to illustrate the application of my improvements includes a rotary folding-bed indicated in a general way by 3. Said folding-bed has a fixed rear portion 4, and a forward portion 5 pivotally mounted at 6 coincident with the main transverse folding line 7 of the bag blank 8. Said portion 5 is provided with opposite clips 9 and 10 for gripping the lower plies of the bag-blank thereto, and 80 fixed portion 4 is provided with opposite clips 11 and 12 for gripping the upper plies of the bag-blank thereto when the forward end of the blank is folded backwardly onto 85 said folding bed portion 4.

Said portion 5 may be rotated in anti-clockwise direction about the axis of shaft 6 through nearly 180 degrees for folding the leading end 13, of the bag-blank onto the fixed rear portion 4 of the folding-bed, and then back again for opening out that leading end into the diamond fold. Shaft 6 may be oscillated at suitable times and clips 9, 10, 11 and 12 operated by known means, not shown.

To increase the accuracy of the operation of clips 11 and 12 in gripping the upper plies 13^a of the bag-blank to the folding bed rear portion 4, there are provided opposite fingers 14 and 18, preferably pivotally mounted for oscillation with shaft 19, above said folding-bed, and said shaft is parallel with the axis of rotation of said folding-bed. These fingers have their operative ends 14^a and 18^a turned inwardly 110

toward each other, whereby they are adapted to enter the opposite side tucks respectively of the bag blank as that blank is delivered tangentially onto the folding-bed, 5 Figs. 1 and 2. Said fingers may be adjustably fixed in heads, as 20, adjustably fixed on shaft 19, and said shaft may be oscillated to cause said fingers to swing as desired, by means of arm 21 fixed to said 10 shaft, and which arm has pivotally attached to its free end connection 22. Said connection 22 may be operably connected with a suitable cam, not shown, on shaft 30. Shaft 19 has bearings in arms, as 23, out-reaching from and fixed to cross rod 24 of the machine.

For assisting the formation of the rearward end of the diamond fold, as folding-bed portion 5 is rotated in clockwise direction from the position of Fig. 6 on through the positions of several of the successive figures, arm 25 is provided. Said arm is preferably pivotally mounted for oscillation on shaft 26 above folding-bed 3 and said 20 shaft is parallel with the axis of rotation of said folding-bed. Said arm is actuated for entering the mouth of the bag-blank, as the leading end of said blank is opened out, and for pressing down the rear end of the 25 diamond fold. Said arm preferably terminates at its free end in a ball 25^a, and the upper end of said arm may be adjustably fixed in head 27 turning freely on said shaft 26. Said head 27 has pivotally attached to 30 a downwardly extending portion thereof, connection 28, which may be operatively connected with a suitable cam, not shown, on shaft 30, and through which means arm 25 may be oscillated.

40 For coaction with said arm 25 in the formation of the rear end of the diamond fold, opposite folders 31 and 32 are provided for turning inwardly and downwardly the rear portion of the sides of the mouth of the bag-blank. These folders are preferably hook-shaped, having at their free ends approximately straight edges 31^a and 32^a the points 45 31^b and 32^b of which are turned upwardly from the plane of movement of said folders, respectively. Said edges 31^a, 32^a, upturned at their ends 31^b, 32^b, conform to the contour of those portions of the bag-blank which they engage, respectively and thereby 50 perform their function without deranging 55 said blank.

Folders 31 and 32 are right and left hand duplicates and a further description of one will suffice for both. Folder 31 is preferably of sheet metal and near that end there- 60 of opposite end 31^b is slotted at 29, and through the slot passes screw 33 for adjustably securing said folder to one end of shaft 34 mounted for oscillation in bearing 35 out-standing from the side of folding-bed 3. 65 The axis of shaft 34 is normal or approxi-

mately normal to the axis of said folding-bed. By this arrangement edge 31^a is tangent to a circle having its center in the axis of shaft 34 and, by adjusting said folder on the head of said shaft the diameter of said circle of tangency may be increased or decreased and the timing of said edge 31^a relatively to the portion of the bag-blank engaged may be varied. Power for oscillating shaft 34 at suitable times may be applied through known means, not shown, to gear 36 fixed to the lower end of said shaft. 70 75

For pressing down the mid-portion of the rear end of the diamond fold in co-operation with arm 25 and folders 31, 32, primary ironer 37 is provided. Said ironer is preferably mounted for oscillation with shaft 42 extraneous to folding-bed 3 and parallel with the axis of said bed. Said ironer is preferably bifurcated at 39 for straddling arm 25 whereby the path of travel of said ironer is permitted to overlap a portion of the path of travel of said arm, see Figs. 7 to 10. For lightness and rigidity of construction said ironer is preferably carried by rod 40, adjustably held in head 41 which is adjustably fixed to shaft 42, and is provided with bracing rod 43 fixed in said head and adjustably secured to rod 40 by dog 44. For oscillating shaft 42, arm 45 80 fixed thereto, has connection 46 pivoted to its free end and the other end of said connection is operatively engaged by a cam, not shown, on shaft 30.

Secondary ironer 47 is adjustably mounted 100 in the free end of arm 48, which for convenience, may be mounted for free rotation on shaft 26. Said ironer is efficient for ironing down and completing the diamond fold after the partially completed fold has been 105 operated upon by the instrumentalities previously described herein. For actuating said ironer there is provided a toggle mechanism comprising arm 49 freely mounted on shaft 42 and link 50, pivoted at one end to 110 the free end of said arm 49 and at the other end to arm 48, about midway the length thereof. When said arm 49 and link 50 are extended in a straight line, see dotted position in Fig. 7, said secondary ironer is in 115 operative relation to folding-bed 3 and just clears that bed. By this arrangement of toggle mechanism, the action of said ironer is had without permitting the ironer to strike the folding-bed, and the mechanism 120 may be run at high speed without noise or jar.

Said ironer 47 is bifurcated at 51 for straddling said primary ironer 37 whereby the paths of travel of said ironers are permitted to overlap and said secondary ironer obtains control of the bag-blank before the primary ironer relinquishes control thereof, thereby insuring continuity of control and accuracy of operation and quality of 125 130

product. For actuating ironer 47, arm 52, which is coaxially mounted with arm 49 and fixed relatively thereto, both being loosely pivoted on shaft 42, has connection 53 pivotally connected to its free end. The other end of said connection 53 is operatively engaged by a cam, not shown, on shaft 30.

The operation of my improved mechanism is as follows: The leading end of the bag-blank is advanced, properly timed, in the direction of travel and at the speed of rotation of the folding-bed into tangential engagement therewith. Clips 9 and 10 thereupon enter the opposite side tucks respectively of the blank and grip the lower plies thereof to the movable portion 5 of the folding-bed. During said advance of the blank, operative ends 14^a and 18^a of fingers 14 and 18 enter the opposite side tucks respectively, said fingers being in a state of rest and the bag-blank passing onto them, see Figs. 1 and 2.

Portion 5 of folding-bed 3 then commences to rotate in anti-clockwise direction about its axis 6 and fingers 14, 18 are swung outwardly away from the folding-bed, ends 14^a, 18^a maintaining their positions within the side tucks respectively through the position of Fig. 3 to that of Fig. 4. Folding-bed 3, continuing its clockwise rotation and portion 5 its anti-clockwise rotation, said portion 5 now moves backwardly and downwardly toward fixed portion 4 of said bed and fingers 14, 18 swing back again toward the folding-bed, Fig. 5, the operative ends thereof still maintaining their positions in the side tucks respectively. Presently the several parts reach positions respectively, shown in Fig. 6 wherein ends 14^a, 18^a of fingers 14, 18 hold the upper plies of the side tucks respectively against the fixed portion 4 of the folding-bed thereby affording side clips 11, 12 free access to said side tucks and enabling those clips to grip said upper plies with accuracy to said portion 4 of the folding bed.

The bag-blank being now in the grip of the two pairs of side clips, said portion 5 of the folding-bed starts on its clockwise movement to open out the mouth of the bag-blank. arm 25 commences its downward movement from the position of Fig. 1 and folders 31, 32 are ready to swing inwardly and forwardly toward each other for turning inwardly the sides of the rear end of the diamond fold, all as shown in Figs. 7 and 15. In Fig. 8 the mouth of the bag-blank has been still further opened and arm 25 has entered therein and has engaged the rear end of the diamond fold. At the same time bifurcated primary ironer 37, straddling arm 25, has commenced to descend from its uppermost position of Fig. 7.

In Fig. 9 arm 25 has pressed the rear end of the diamond fold downwardly toward the

folding-bed sufficiently to permit folders 31, 32 to rotate toward each other in the direction of travel of the folding-bed, as shown, thereby turning inwardly the sides of the rear end of the diamond fold. During these movements, portion 5 of the folding-bed has coacted by continuing its clockwise movement and primary ironer 37 has continued its downward movement toward the bag-blank on the folding-bed and is about ready to enter the mouth thereof. See also the plan view of Fig. 16.

After having performed their function of turning inwardly the sides of the rear end of the diamond fold, folders 31, 32 immediately return to their outer positions of Fig. 17 where they remain until called into operation on the next succeeding blank.

From the position of Fig. 9 to that of Fig. 10, arm 25 continues to swing in anti-clockwise direction, slightly faster than the bag-blank is advanced by the folding-bed, but not so fast as primary ironer 37 moves in the same direction. Therefore said ironer passes down into the mouth of the blank ahead of said arm and that arm swings over its rear end, Fig. 11. At the same time secondary ironer 47 commences to descend from its position of Figs. 7 and 10 to that of Fig. 11 with its rearward bifurcated end straddling primary ironer 37.

In Fig. 12 folding-bed portion 5 has returned to coincidence with the general periphery of the folding-bed, thereby completing its function of opening out the mouth of the blank for forming the diamond fold; arm 25 has started on its clockwise return movement, and engages for a moment the rear end of the diamond fold; primary ironer 37 has reached its position of nearest approach to the folding-bed and the rearward end of the diamond fold is held down thereby; also secondary ironer 47 has continued to descend and is about to engage the bag blank. In Fig. 13 arm 25 continues its clockwise movement and has ceased to influence the bag blank; primary ironer 37 maintains its position of Fig. 12 and secondary ironer 47 has begun to iron down the diamond fold.

In Figs. 14 and 17 the diamond fold is just passing out from under primary ironer 37 and secondary ironer 47 has reached its limit of movement toward the folding-bed and has completed the ironing of the diamond fold. Between the positions of Figs. 13 and 14 side clips 11, 12 withdraw to permit secondary ironer 47 to suitably iron the blank without interference, see Fig. 17, but said clips may regrip the blank later if desired.

The function of my improved mechanism is now completed and the bag-blank, continuing its clockwise movement, may pass out from under ironer 47 to suitable mecha-

nism, not shown, for transforming the diamond fold into a completed bag bottom.

I claim:

1. In a paper bag machine employing a 5 rotatable folding-bed, means for holding a bag-blank thereon, means for folding over the upper plies of the side tucks onto the folding-bed and means for gripping those upper plies to the folding-bed, the combination 10 of opposite fingers movably mounted extraneous to said folding-bed and adapted to enter the opposite side tucks respectively of said bag-blank as that blank is delivered onto the folding-bed and actuated to follow 15 the upper plies of said side tucks as they are folded over onto the folding-bed and then to hold those upper plies against said folding-bed until the upper ply gripping means 20 grips said upper plies respectively to the folding bed.

2. In a paper bag machine employing a 25 rotatable folding-bed comprising two portions one of which is actuated to be folded backwardly to deliver the upper plies of the side tucks of the leading end of the blank against the other portion of said folding-bed, said other portion being provided with gripping means, the combination of opposite 30 fingers pivotally mounted extraneous to the folding-bed and adapted to enter the opposite side tucks respectively of the bag-blank as that blank is delivered onto the folding-bed, means for swinging said fingers away from the folding-bed as the leading end of 35 said bag-blank is folded upwardly relatively to said folding-bed—and for swinging said fingers toward said folding-bed as the leading end of said bag-blank is folded backwardly and downwardly toward said 40 folding-bed and for holding the upper plies of said side tucks respectively against the other portion of the folding-bed, whereby the said gripping means are afforded free 45 access to said side tucks and are enabled to grip said upper plies respectively with accuracy at predetermined points to said other portion of the folding-bed.

3. In a paper bag machine employing a 50 rotatable folding-bed, means for holding a bag-blank thereon, means for folding over the upper plies of the side tucks onto the folding bed and means for gripping those upper plies to the folding-bed, the combination 55 of opposite fingers pivotally mounted extraneous to the folding-bed and on an axis parallel with the axis of the folding-bed and adapted to enter the opposite side tucks respectively of the bag-blank as that blank is delivered onto the folding-bed and 60 actuated to follow the upper plies of said side tucks as those side tucks are folded over onto the folding-bed and then to hold those upper plies against said folding-bed until the upper ply gripping means grip said 65 upper plies respectively to the folding-bed.

4. In a paper bag machine employing a rotatable folding-bed comprising two portions one of which is actuated for folding backwardly onto the other portion thereof the leading end of the bag-blank and means 70 on each folding-bed portion for gripping the bag-blank, the combination of fingers extraneous to said folding-bed adapted and actuated for entering the side tucks of the bag-blank and for accompanying that blank 75 during its backward folding and for holding the upper plies of those side tucks against the other portion of the folding-bed until the gripping means on said other portion have gripped said upper plies respectively to said other portion, and an arm 80 movably mounted extraneous to the folding-bed and adapted and actuated for entering the mouth of the blank as the leading end of that blank is opened out during the return of the backwardly folding portion of the folding-bed to its initial position, to assist the folding of the rear portion of the diamond fold.

5. In a paper bag machine employing a 90 rotatable folding-bed comprising two portions one of which is movable and actuated for folding backwardly onto the other portion thereof the leading end of the bag-blank, means on each folding-bed portion 95 for gripping the bag-blank, the movable portion of said folding-bed being efficient upon its return movement to open out the leading end of the blank, the combination of an arm 100 movably mounted extraneous to the folding-bed and actuated for entering the mouth of the bag-blank as the leading end of said blank is opened out, and for pressing down the rear end of the diamond fold.

6. In a paper bag machine employing a 105 rotatable folding-bed comprising two portions one of which is movable and actuated for folding backwardly onto the other portion thereof the leading end of the bag-blank, means on each folding-bed portion 110 for gripping the bag-blank, the movable portion of said folding-bed being efficient upon its return movement to open out the leading end of the blank, the combination of an arm 115 movably mounted extraneous to the folding-bed and actuated for entering the mouth of the bag blank as the leading end of said blank is opened out, and for pressing down the rear end of the diamond fold, and opposite folders carried by the folding-bed 120 and mounted for movement toward each other and in the direction of travel of said folding-bed for turning inwardly the sides of the rear end of the diamond fold during 125 the operation of said arm.

7. In a paper bag machine employing a rotatable folding-bed comprising two portions one of which is movable and actuated for folding backwardly onto the other portion thereof the leading end of the bag- 130

- blank, means on each folding-bed portion for gripping the bag-blank, the movable portion of said folding-bed being efficient upon its return movement to open out the 5 leading end of the blank, the combination of an arm pivotally mounted extraneous to the folding-bed on an axis parallel with the axis of the folding-bed and actuated for entering the mouth of the bag-blank as the 10 leading end of said blank is opened out and for pressing down the rear end of the diamond fold, and opposite folders pivotally mounted on the folding-bed on axes respectively normal to the axis of rotation of said 15 folding-bed and actuated rotatively toward each other in the direction of travel of said folding-bed for turning inwardly the sides of the rear end of the diamond fold during the operation of said arm.
- 20 8. In a paper bag machine employing a rotatable folding-bed and having means for opening out the leading end of the bag-blank into the diamond fold, the combination of an arm movably mounted extraneous to the 25 folding-bed and actuated for entering the mouth of the bag-blank as the leading end of said blank is opened out, and for pressing down the rear end of the diamond fold, and a primary ironer movably mounted extraneous to said folding-bed and actuated for pressing down the mid-portion of the rear end of the diamond fold subsequent to the 30 operation of said arm.
9. In a paper bag machine employing a 35 rotatable folding-bed comprising two portions one of which is movable and actuated for folding backwardly onto the other portion thereof the leading end of the bag-blank, means on each folding-bed portion 40 for gripping the bag-blank, the movable portion of said folding-bed being efficient upon its return movement to open out the leading end of the blank, the combination of an arm movably mounted extraneous to 45 the folding-bed and actuated for entering the mouth of the bag-blank as the leading end of said blank is opened out, and for pressing down the rear end of the diamond fold, opposite folders carried by the folding- 50 bed and mounted for movement toward each other and in the direction of travel of said folding-bed for turning inwardly the sides of the rear end of the diamond fold during the operation of said arm, and a primary ironer 55 movably mounted extraneous to said folding-bed and actuated for pressing down the mid-portion of the rear end of the diamond fold subsequent to the operation of said arm.
- 60 10. In a paper bag machine employing a rotatable folding-bed and having means for opening out the leading end of the bag-blank into the diamond fold, the combination of an arm pivotally mounted ex- 65 traneous to the folding-bed on an axis par-
- allel with the axis of the folding-bed and actuated for entering the mouth of the bag blank as the leading end of said blank is opened out and for pressing down the rear end of the diamond fold, opposite folders 70 pivotally mounted on the folding-bed on axes respectively normal to the axis of rotation of said folding bed and actuated rotatively toward each other in the direction of travel of said folding bed for turning 75 inwardly the sides of the rear end of the diamond fold during the operation of said arm, and a primary ironer pivotally mounted extraneous to the folding-bed on an axis parallel with the axis of rotation of the 80 folding-bed and actuated for pressing down the mid-portion of the rear end of the diamond fold subsequent and supplemental to the operation of said arm.
11. In a paper bag machine employing a 85 rotatable folding-bed and having means for opening out the leading end of the bag blank into the diamond fold, the combination of an arm pivotally mounted extraneous to the folding-bed on an axis parallel with the axis 90 of the folding-bed and actuated for entering the mouth of the bag-blank as the leading end of said blank is opened out and for pressing down the rear end of the diamond fold, opposite folders pivotally mounted on the folding-bed on axes respectively normal to the axis of rotation of said folding-bed and actuated rotatively toward each other in the direction of travel of said folding- 95 bed for turning inwardly the sides of the rear end of the diamond fold during the operation of said arm, and a primary ironer pivotally mounted extraneous to the folding-bed on an axis parallel with the axis of rotation of the folding-bed, said ironer being 100 bifurcated for straddling said arm, whereby the path of travel of said ironer is permitted to overlap a portion of the path of travel of said arm.
12. In a paper bag machine employing a 105 rotatable folding-bed comprising two portions one of which is movable and adapted and actuated for folding backwardly onto the other portion thereof the leading end of the bag-blank, means on each folding-bed portion for gripping the bag-blank, the movable portion of said folding-bed being efficient upon its return movement to open out the leading end of the blank, the combination of an arm movably mounted ex- 110 traneous to the folding-bed and actuated for entering the mouth of the bag-blank as the leading end of said blank is opened out, and for pressing down the rear end of the diamond fold, and opposite folders pivotally mounted on the folding-bed on axes respectively normal to the axis of rotation of said folding-bed and actuated rotatively toward each other in the direction of travel 115 of said folding-bed for turning inwardly the 120
- 130

sides of the rear end of the diamond fold during the operation of said arm, said folders terminating in an edge which at the point of engagement with the rear end of the diamond fold is in substantial conformity with the portion engaged.

13. In a paper bag machine employing a rotatable folding-bed comprising two portions one of which is movable and actuated for folding backwardly onto the other portion thereof the leading end of the bag-blank, means on each folding-bed portion for gripping the bag-blank, the movable portion of said folding-bed being efficient upon its return movement to open out the leading end of the blank, the combination of an arm movably mounted extraneous to the folding-bed and actuated for entering the mouth of the bag-blank as the leading end of said blank is opened out, and for pressing down the rear end of the diamond fold, opposite folders pivotally mounted on the folding-bed on axes respectively normal to the axis of rotation of said folding-bed and actuated rotatively toward each other in the direction of travel of said folding-bed for turning inwardly the sides of the rear end of the diamond fold during the operation of said arm, each of said folders terminating in an approximately straight edge tangent to a circle having its center in the pivotal axis of said finger, and means for adjusting said finger to vary the diameter of the circle of tangency and the timing of operation.

14. In a paper bag machine employing a rotatable folding-bed and having means for opening out the leading end of the bag-blank into the diamond fold, the combination of an arm movably mounted extraneous to the folding-bed and actuated for entering the mouth of the bag-blank as the leading end of said blank is opened out, and for pressing down the rear end of the diamond fold, a primary ironer movably mounted extraneous to said folding-bed and actuated for pressing down the mid-portion of the rear end of the diamond fold subsequent to the operation of said arm, and a secondary ironer movably mounted extraneous to the folding-bed and actuated for ironing down the leading end of the diamond fold and for remaining in its operative position until the rear end of the diamond fold passes thereunder.

15. In a paper bag machine employing a rotatable folding-bed and having means for opening out the leading end of the bag-blank into the diamond fold, the combination of an arm movably mounted extraneous to the folding-bed and actuated for entering the mouth of the bag-blank as the leading end of said blank is opened out, and for pressing down the rear end of the diamond fold,

a primary ironer pivotally mounted extraneous to the folding-bed on an axis parallel with the axis of rotation of the folding-bed, said ironer being bifurcated for straddling said arm whereby the path of travel of said ironer is permitted to overlap a portion of the path of travel of said arm, a secondary ironer movably mounted extraneous to the folding-bed, said ironer being bifurcated for straddling said primary ironer whereby said ironers are permitted to overlap in their paths of travel respectively, and means for actuating said ironers.

16. In a paper bag machine employing a rotatable folding-bed and having means for opening out the leading end of the bag-blank into the diamond fold, the combination of an arm pivotally mounted extraneous to the folding-bed on an axis parallel with the axis of the folding-bed and actuated for entering the mouth of the bag-blank as the leading end of said blank is opened out and for pressing down the rear end of the diamond fold, a primary ironer movably mounted extraneous to said folding-bed, said ironer being bifurcated for straddling said arm whereby the path of travel of said ironer is permitted to overlap a portion of the path of travel of said arm, a secondary ironer movably mounted extraneous to the folding-bed, said ironer being bifurcated for straddling said primary ironer whereby said ironers are permitted to overlap in their paths of travel respectively, and means for actuating said ironers.

17. In a paper bag machine employing a rotatable folding-bed and having means for opening out the leading end of the bag-blank into the diamond fold, the combination of a primary ironer pivotally mounted extraneous to the folding-bed on an axis parallel with the axis of rotation of the folding-bed and actuated for pressing down the mid-portion of the rear end of the diamond fold, a secondary ironer pivotally mounted extraneous to the folding-bed on an axis parallel with the axis of rotation of the folding-bed, said ironer being bifurcated for straddling said primary ironer whereby the paths of travel of said ironers are permitted to overlap, and means for actuating said secondary ironer.

18. In a paper bag machine employing a rotatable folding-bed and having means for opening out the leading end of the bag-blank into the diamond fold, the combination of a primary ironer movably mounted extraneous to said folding-bed and actuated for pressing down the mid-portion of the rear end of the diamond fold, a secondary ironer movably mounted extraneous to the folding-bed, said ironer being bifurcated for straddling said primary ironer whereby said ironers are permitted to overlap in their

paths of travel respectively, and toggle means for moving said secondary ironer toward and from the folding-bed.

19. In a paper bag machine employing a rotatable folding-bed and having means for opening out the leading end of the bag-blank into the diamond fold, the combination of a primary ironer pivotally mounted extraneous to the folding-bed on an axis parallel with the axis of rotation of the folding-bed and actuated for pressing down the mid-portion of the rear end of the diamond fold, a secondary ironer pivotally mounted extraneous to the folding-bed on an axis parallel with the axis of rotation of the folding-bed, said ironer being bifurcated for straddling said primary ironer whereby the paths of travel of said ironers are permitted to overlap, and toggle means for oscillating said secondary ironer relatively to said folding-bed.
